UNITED STATES PATENT OFFICE.

WILLIAM A. GILE, OF CLIFTONDALE, MASSACHUSETTS, ASSIGNOR, BY MESNE ASSIGNMENTS, TO GEORGE K. WOODWORTH, TRUSTEE, OF BROOKLINE, MASSACHUSETTS.

INTERNAL-COMBUSTION ENGINE.

1,335,324.

Specification of Letters Patent. Patented Mar. 30, 1920.

Application filed May 9, 1916. Serial No. 96,422.

To all whom it may concern:

Be it known that I, WILLIAM A. GILE, a citizen of the United States, and a resident of Cliftondale, in the county of Essex and State of Massachusetts, have invented a new and useful Improvement in Internal-Combustion Engines, of which the following is a specification.

My invention relates to internal combustion engines and more especially to engines of the combined pump and motor cylinder type, either single or double acting, and its object is to provide a simple and efficient means actuated by an auxiliary crank on the crank-shaft for controlling the motion of the sub-piston.

The drawings which accompany and form a part of this specification show an illustrative embodiment of my invention, but it is to be understood that the construction herein particularly described may be widely varied without departing from the scope of my invention as defined by the appended claims.

25 In the drawings—

Figure 1 is a central longitudinal section of a single-acting engine embodying my improved sub-piston control. Fig. 2 is a central longitudinal section taken on the line 2—2 of Fig. 1. Figs. 3, 4, 5 and 6 are diagrams showing the positions of the moving parts at various points in the cycle.

In the particular drawings selected for more fully disclosing my invention, 1 represents a frame herein shown as a two-part casing having its parts connected by the bolts 2 and inclosing the lower portion of the engine. Secured to the top of the casing by the bolts 3 is a cylinder 4, the lower end of which is open and communicates with said casing and the upper end of which is closed by the head 5 attached by the bolts 6 and is provided with a number of fuel passages or flutes arranged lengthwise in its bore and communicating with the combustion chamber A. Any suitable number of flutes, say from 16 to 20, more or less, may be used. A spark-plug 8 is screwed into the cylinder head, its points projecting into the combustion chamber, and the cylinder and head are water-jacketed as shown at 9, 10.

Arranged to reciprocate within the cylinder is a power piston 11, herein shown as

a trunk piston or plunger, and two rods 12 screwed into the lugs 13 projecting inwardly from the walls of the piston connect said piston with the hollow cross-head 14 guided by the ways 15, the lower ends of said rods being shown in the present instance as threaded into the upper portion 60 of said cross-head. It will be understood, however, that any suitable means may be employed for connecting the piston to its cross-head. A pitman 16 engages the pin 17 extending across the interior of said cross-head and connects said piston to the wrist pin 18 of the main crank 19 to transmit the power developed in the cylinder to the crank-shaft 20 journaled in the bearings 20' which are integral with the engine 70 frame.

A sub-piston 21 is arranged to reciprocate within the cylinder between the power piston and the combustion chamber A and its rod 22 passes through and is guided by 75 a longitudinal bore in the central core of the power piston, its lower end being secured to the cross-head 23 by threaded engagement therewith, a lock-nut 24 being employed if desired to prevent relative 80 movement between said rod and cross-head. It will be understood of course that I do not limit myself to this particular mode of attaching the rod of the sub-piston to its cross-head. The ends of the cross-head 23 85 are grooved vertically at 25 and the rods 12 fit into said grooves and thereby act as guides for said cross-head.

The connecting rod 26 is pivotally connected to a stud 27 projecting from one side 90 of the cross-head 23 and to the upper end of the rocker-arm 28 which is pivoted to the stud 29 attached to the frame and extending inwardly therefrom. A connecting rod 30 engages the lower end of said rocker-arm 95 and its hub 31 is connected by the wrist pin 32 to the auxiliary crank 33, one arm of said crank forming in the present instance an extension of an arm of the main crank 19, although this is not essential.

The cylinder has an exhaust passage 34 controlled by the inwardly opening valve 35 normally held to its seat by the spring 36 which surrounds the valve stem 37 and bears against the valve housing and the collar 38 105 on said stem. The valve may be opened by

any suitable mechanism, such for example as the tappet 39 actuated by the cam 40 which coöperates with the head 41 thereof, gearing (not shown) being employed to connect the 5 cam shaft 42 with the crank-shaft.

The fuel-inlet 43 is located a short distance above the lower end of the power piston when the latter is in explosion position at the end of its up-stroke, as shown in 10 Fig. 2, and may be connected to any suitable source of fuel.

It will be understood of course that the foregoing detailed description comprises various elements which in the precise form 15 shown in the drawings and described herein are not essential to my invention and that these parts may be considered simply as typical of the necessary elements of an internal combustion engine.

20 By means of the flutes or fuel passages 7 I secure an intimate and substantially perfect mixture of the fuel charge and this results in practically complete combustion. As the power piston approaches the head of 25 the sub-piston the charge which is contained in the space between these two elements is compressed and forced by such compression around the advancing head of the sub-piston through the restricted passage afforded by 30 the flutes or fuel passages and is shot with great force against the cylinder head in a number of relatively small streams.

An explosion of the compressed charge in the combustion chamber acts directly on the 35 head of the sub-piston and by the latter is communicated to the power piston. It is absolutely necessary that the two pistons shall travel at the same rate of speed without the slightest relative movement until the 40 sub-piston shall have covered the inner ends of the flutes. The reason for this will be obvious from an inspection of Fig. 2 in which the parts are shown in the position occupied immediately prior to ignition in 45 the combustion chamber A. Should the power piston begin to move away from the sub-piston before the latter covers the inner ends of the flutes, a portion of the effect of the explosion will be exerted against the 50 lower face of said sub-piston in opposition to the force exerted on the upper face thereof. It is essential also that the subsequent relative movement between the pistons shall be created positively.

55 The positive relative movement of the sub-piston with respect to the power piston is created by the auxiliary crank 33 which communicates the necessary motion to the sub-piston through the connecting rod 30, 60 rocker-arm 28 and rod 26. The operation of these elements will be explained with reference to Figs. 3, 4, 5 and 6, on which the several moving parts are indicated by lines identified by the reference numerals cor- 65 responding to those used on Figs. 1 and 2

and provided with exponents I, II, III, etc., to designate the successive positions of the parts.

When both pistons are at the upper ends of their strokes (explosion position) as 70 shown in Figs. 1, 2 and 3, and the charge compressed in the combustion chamber, the valve 35 being closed, the charge is fired and the resulting explosion causes both pistons to descend at the same initial rate of speed 75 and without any relative movement substantially until the power crank 19 which rotates in the direction of the arrows, has passed from its initial position (Fig. 3) sufficiently beyond its position 19' (Fig. 4) to bring the 80 auxiliary crank 33 and the connecting rod 30 in alinement. At this point the sub-piston is at the lower end of its stroke with its lower face a little above the fuel inlet 43 and the upper face of the power piston is a 85 little below said inlet. The sub-piston, just before reaching the end of its stroke begins to lag and the power piston moves away therefrom.

The power piston continues its descent until it reaches position 11", the end of its down-stroke (Fig. 5) the power crank now being at 19", but as soon as the sub-piston reached the end of its down-stroke and while the power piston was moving from 11' to 95 11", the former began to ascend, the rocker-arm being rotated clockwise by the continued rotation of the auxiliary crank 33 from its position in alinement with the rod 30 and thereby forcing the rod 26 upwardly, 100 so that in the position of the parts represented in Fig. 5, the power piston is momentarily stationary and the sub-piston moving upwardly. The relative movement between the pistons creates a vacuum or a partial 105 vacuum in the space between the same in which a charge of fuel is drawn from the inlet 43, and, as will be apparent, the pumping action which sucks in said charge is created mainly by the rapid upward move- 110 ment of the sub-piston because the power piston travels but a short distance from the position it occupies at the end of the down-stroke of the sub-piston to its position 11" which is the end of its own down-stroke. 115

The exhaust valve 35 opens practically simultaneously with or preferably shortly before the commencement of the up-stroke of the sub-piston and the burnt gases of the previous explosion are mechanically expelled 120 by the latter. The power crank continuing its counter-clockwise rotation, the power piston ascends and when the former reaches a point about 240 degrees from its initial position, shown at 19'", Fig. 6, the sub-piston 12 has arrived at the end of its up-stroke occupying the position 21"" which is above explosion position, the rocker-arm 28 being in line with the connecting rod 26 (Fig. 6). Further rotation of the auxiliary crank to 13

- the positions 33^{iv}, 33^v back to its initial position 33 will cause the sub-piston to settle back very slightly to 21^{iv}, or slightly below 21^{iv}, then rise to 21^v and to 21^{vi}, and finally 5 when said auxiliary crank has reached its initial position the sub-piston will fall back to explosion position 21. In other words, the sub-piston rises to the position 21^{vi} remains practically stationary and then falls 10 back to explosion position. By rising above explosion position it will more effectively expel the burnt gases from the combustion chamber A. The positions of the rocker-arm corresponding with those of the auxiliary crank 33^{iv} 33^v and 33 are indicated in dotted lines at 28^{iv} 28^v and 28, respectively. The dotted lines marked 21^{iv} 21^v and 21 represent the corresponding positions of the lower face of the sub-piston. 15
- 20 Shortly before the sub-piston arrives at its position 21^{vi}, the power piston has covered the fuel inlet and thereafter it compresses the charge in the space between its upper face and the lower face of the sub-piston. A portion of the gas so compressed passes around the head of the sub-piston through the flutes to the combustion chamber and pneumatically expels the small portion 25 of the burnt gas which was not mechanically expelled therefrom, and thereupon the exhaust valve closes. The power piston then continues its upward stroke, further compressing the charge and driving the same with great force through the flutes 30 into the combustion chamber thereby shooting the charge against the cylinder-head in a plurality of relatively small streams and effecting the thorough mixture of the same, until both cranks having arrived at their 35 initial positions 19 and 33 respectively, the up-stroke of the power piston is completed, and, the sub-piston then being in explosion position as above explained, ignition takes place and the cycle is repeated, there being 40 one explosion at the end of every up-stroke or one per revolution of the crank-shaft. 45

It will be obvious that by duplicating the sub-piston control apparatus, my invention may be applied to a double-acting engine 50 having two sub-pistons, one on each side of the power-piston.

While I have described in detail the relative movement of the parts which I have found to be satisfactory in practice, it will 55 be understood that I do not limit myself specifically thereto, for said parts may be variously adjusted and timed and other cycles may be effected.

I claim:

- 60 1. An internal combustion engine comprising a cylinder, a power piston and a sub-piston both arranged to reciprocate within said cylinder and to travel in the same direction during the power stroke, a 65 main shaft provided with two cranks, means

actuated by one crank for controlling said sub-piston positively throughout the entire cycle, said means being constructed for causing said sub-piston to travel in contact with said power piston during a substantial portion of the power stroke and for causing, subsequently, relative movement between said pistons, and a pitman connecting said power piston to the other crank. 70

2. An internal combustion engine comprising a cylinder, a power piston and a sub-piston both arranged to reciprocate within said cylinder and to travel in the same direction during the power stroke, a main shaft provided with two diametrically opposed cranks, means actuated by one crank for controlling said sub-piston positively throughout the entire cycle, said means being constructed for causing said sub-piston to travel in contact with said power piston during a substantial portion of the power stroke and for causing, subsequently, relative movement between said pistons, and a pitman connecting said power piston to the other crank. 80

3. An internal combustion engine comprising a cylinder, a power piston and a sub-piston both arranged to reciprocate within said cylinder, a main shaft having a power crank and an auxiliary crank, a pitman connecting said power piston to said power crank, and means actuated by said auxiliary crank for causing positive movement of said pistons in the same direction at the same initial rate and for causing, 95 subsequently, positive relative movement between the same. 100

4. An internal combustion engine comprising a cylinder, a power piston and a sub-piston both arranged to reciprocate within said cylinder, a main shaft having a power crank and an auxiliary crank, a pitman connecting said power piston to said power crank, and means actuated by said auxiliary crank for causing positive movement of said pistons initially at the same rate of speed without relative movement and subsequently at different rates. 110

5. An internal combustion engine comprising a cylinder, a power piston and a sub-piston both arranged to reciprocate within said cylinder, said sub-piston being located between the combustion chamber and the power piston, a main shaft having a power crank and an auxiliary crank, a 115 rocker-arm pivoted adjacent to said shaft, a connecting rod pivotally engaging said auxiliary crank and one end of said rocker-arm, a cross-head secured to the rod of said sub-piston, and a rod pivotally connecting the other end of said rocker-arm and said cross-head. 120

6. An internal combustion engine comprising a cylinder, a power piston and a sub-piston both arranged to reciprocate 125

within said cylinder, said sub-piston being located between the combustion chamber and the power piston, a main shaft having a power crank and an auxiliary crank, a rocker-arm pivoted adjacent to said shaft, a connecting rod pivotally engaging said auxiliary crank and one end of said rocker-arm, and means connecting the other end of said rocker-arm to the rod of said sub-piston.

7. An internal combustion engine comprising a cylinder, a power piston and a sub-piston both arranged to reciprocate within said cylinder, a main shaft having a power crank and an auxiliary crank, a pitman connecting said power piston to said power crank, and means actuated by said auxiliary crank for causing said pistons to travel in the same direction at the same rate of speed until the sub-piston reaches substantially the end of its stroke and for causing, subsequently, positive relative movement between the same.

8. An internal combustion engine comprising a cylinder, a power piston and a sub-piston both arranged to reciprocate within said cylinder, a main shaft having a power crank and an auxiliary crank, a pitman connecting said power piston to said power crank, means actuated by said auxiliary crank for causing said pistons to travel in the same direction at the same rate of speed until the sub-piston reaches substantially the end of its down-stroke, for causing, subsequently, positive relative movement between the same, for projecting the sub-piston above explosion position and then recalling it to explosion position.

9. An internal combustion engine comprising a cylinder, a power piston and a sub-piston both arranged to reciprocate within said cylinder, a cross-head, a guide for said cross-head, members connecting said power piston to said cross-head, a pitman pivotally connecting said cross-head to the power crank, a second cross-head guided by said members, means connecting said sub-piston to the last mentioned cross-head, and a rod pivotally connecting the last mentioned cross-head to a moving part of the engine.

10. An internal combustion engine comprising a cylinder provided with a combustion chamber at one end only, a sub-piston and a power piston both arranged to reciprocate within said cylinder, said sub-piston having a single head located between said combustion chamber and said power piston, a main shaft having a power crank and an auxiliary crank, a pitman connecting said power piston to said power crank, means for causing the sub-piston to travel in contact with the power piston during a substantial portion of the power stroke and for causing, subsequently, positive relative

movement between said pistons, and a member connecting said means to said auxiliary crank.

11. An internal combustion engine comprising a cylinder, a power piston and a sub-piston both arranged to reciprocate within said cylinder, a main shaft having a power crank and an auxiliary crank, a pitman connecting said power piston to said power crank, means actuated by said auxiliary crank for causing positive movement of said pistons at the same initial rate of speed without relative movement and for causing, subsequently, positive relative movement between the same, and means whereby the charge of fuel in said cylinder is transferred under pressure from the space between said pistons through a restricted passage to the combustion chamber.

12. An internal combustion engine comprising a cylinder, a power piston and a sub-piston both arranged to reciprocate within said cylinder, a main shaft having a power crank and an auxiliary crank, a pitman connecting said power piston to said power crank, means actuated by said auxiliary crank for causing positive movement of said pistons at the same initial rate of speed without relative movement and for causing, subsequently, positive relative movement between the same, and means whereby the charge of fuel in said cylinder is mixed during compression.

13. An internal combustion engine comprising a cylinder, a power piston and a sub-piston both arranged to reciprocate within said cylinder, a main shaft having a power crank and an auxiliary crank, a pitman connecting said power piston to said power crank, means actuated by said auxiliary crank for causing positive movement of said pistons at the same initial rate of speed without relative movement and for causing, subsequently, positive relative movement between the same, and means whereby the charge of fuel in said cylinder is transferred under pressure from the space between said pistons to the combustion chamber in a plurality of relatively small streams.

14. An internal combustion engine comprising a cylinder having a plurality of fuel passages arranged lengthwise in its bore at one end thereof, a power piston and a sub-piston both arranged to reciprocate within said cylinder, a main shaft having a power crank and an auxiliary crank, a pitman connecting said power piston to said power crank, and means actuated by said auxiliary crank for causing positive movement of said pistons at the same initial rate of speed without relative movement, and for causing, subsequently, positive relative movement between the same.

15. An internal combustion engine com-

prising a cylinder having a plurality of fuel passages arranged in its bore near one end thereof, said fuel passages communicating with the combustion chamber of the engine, 5 a power piston and a sub-piston both arranged to reciprocate within said cylinder, a main shaft having a power crank and an auxiliary crank, a pitman connecting said power piston to said power crank, and 10 means actuated by said auxiliary crank for causing positive movement of said pistons at the same initial rate of speed without relative movement and for causing, subsequently, positive relative movement between 15 the same.

16. An internal combustion engine comprising a cylinder provided with a combustion chamber, a sub-piston and a power piston both arranged to reciprocate within said cylinder, said sub-piston being located between said combustion chamber and said power piston, a main shaft having a power crank and an auxiliary crank, a pitman connecting said power piston to said power 25 crank, means for causing the sub-piston to travel in contact with the power piston during a substantial portion of the power stroke and for causing, subsequently, positive relative movement between said pistons, and a 30 member connecting said means to said auxiliary crank.

17. An internal combustion engine com-

prising a cylinder, a sub-piston and a power piston both arranged to reciprocate within said cylinder, a main shaft having a crank 35 and an auxiliary crank, a pitman connecting said power piston to said power crank, means for causing the sub-piston to travel in contact with the power piston during a substantial portion of the power stroke and 40 for causing, subsequently, positive relative movement between said pistons, and a member connecting said means to said auxiliary crank.

18. An internal combustion engine comprising a cylinder, a power piston and a sub-piston both arranged to reciprocate within said cylinder and to travel in the same direction during the power stroke, said sub-piston being located between the combustion chamber and the power piston, a shaft provided with two cranks, means for controlling said sub-piston positively throughout the entire cycle, a member connecting said means to one of said cranks, and a 50 pitman connecting said power piston to the other crank.

In testimony whereof I have hereunto subscribed my name this 22nd day of April, 1916.

WILLIAM A. GILE.
